Fig. 3.

UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed October 5, 1921. Serial No. 505,604.

To all whom it may concern:

Be it known that I, JOHN WALDHEIM, a citizen of the United States, residing in Elizabeth, in the county of Union and State of New Jersey, have invented certain new and useful Improvements in Typewriting Machines, of which the following is a specification.

This invention relates to sound-deadening cases or cabinets for typewriting machines.

It is one feature of this invention to provide a sound-deadening casing which is supported upon the machine so that it may readily be transported therewith and which completely encloses the noise-producing parts thereof. To this end, the casing may comprise a base-plate which is secured to the bottom of the machine frame and a hood which fits over the machine and is supported on said base-plate.

A further feature of this invention is the provision of means whereby the hood can readily be applied to or removed from the machine.

The hood comprises a body-part and a cover-part hinged to said body-part. It is another feature of this invention to mount the cover-part upon the body-part in such manner as to enable the cover-part to be opened with a minimum of effort. For this purpose, the pivotal axis of the cover-part is positioned between the forward and rearward edges thereof, so that the weight of said cover-part is distributed to the front and rear of said axis, or, in other words, the pivot is approximately under the center of gravity of said cover.

A further feature of this invention is the mounting of the cover-part upon the body-part in such manner that the forward edge of said cover-part, when the latter is in raised or open position, shall not extend upwardly to such height as to render it inconvenient for the operator to reach the cover-part when it is desired to lower said part. For this purpose, the pivotal axis of the cover-part is positioned below the upper edges of the body-part so that the forward edge of said cover-part, when the latter is in raised position, will be positioned correspondingly low.

Other features and advantages will hereinafter appear.

In the accompanying drawings,

Figure 1 is a side view, vertically sectioned, of the sound-deadening means applied to an Underwood Standard typewriting machine.

Figure 2 is a similar view of the sound-deadening means, but detached from the machine, and the base-plate, the cover-part of the hood being in open position.

Figure 3 is a front view, partly sectioned, of the device shown in Figure 1.

The Underwood Standard typewriting machine comprises a main frame 10 supported upon a base by feet 11, said machine having a forward extension 12 in which are positioned banks of keys 13, operating type-bars 14 to cause types 15, carried thereby, to strike against the front of a platen 16 journaled in a platen-frame 17. Said frame forms part of a carriage 20 mounted for letter-feeding movement upon a front rail 21 and a rear rail 22 on the main frame. The carriage may be provided with various forwardly-extending operating finger-pieces, such as a line-space lever 23.

For deadening the sounds arising in the typing operation, there is provided sound-deadening means comprising a base 25 and a hood 26 (see Figure 2). The base 25 is in the form of a plate which closes the bottom opening of the typewriting machine, and is secured to the machine preferably between the main frame 10 and the supporting feet 11. For enclosing the machine above the base 25, there is provided the hood 26 consisting of a body-part 30 and a cover-part 31. The hood is open at the bottom, said opening being sufficiently large so that the hood may be moved downwardly over the typewriting machine when the typewriter-carriage is in its central position. The base 25 is preferably provided with an upwardly-extending flange 33 with which the lower edge of the body-part contacts to position the hood relatively to the base and the machine. The body-part comprises a rear wall 35, a front wall 36, and side walls 37, said body-part being provided with lateral extensions 38 over which the typewriter-carriage may operate to the right and left.

After the hood has been applied to the machine, it may be held in position on the base 25 by spring-pressed latches or snap

2
hooks 40 which become effective automatically, or, in other words, snap into holding position as soon as the hood reaches said base while being slid downwardly over the machine. When the hood is to be detached from the base, the hooks 40 are released and the hood lifted upwardly.

For enclosing the machine at the top, the hood is provided with the cover-part 31 in the form of a swing frame having side walls 49 extending downwardly below the upper edges of the body-part and overlapping the sides of the body-part, and a top wall or ceiling 42, said ceiling being preferably provided with a window 43 to permit the machine in the interior of the casing to be viewed. The cover-part is pivoted on screws or studs 49^a. If the pivotal axis of the cover-part were located at the rear thereof, the entire weight of the cover-part would have to be overcome in lifting the cover-part to open position, resulting in a heavy lifting action. To produce an easy lifting action, the pivotal axis is positioned between the forward and rearward edges of the cover-part, so that the weight of the cover-part is thus distributed to the front and rear of the pivotal axis, the greater portion of the weight of the cover-part being positioned forwardly of said axis, so that, when said cover-part is lowered, it will remain in lowered position, due to gravity. In other words, with this arrangement, the center of gravity of the cover is changed from one side to the other of a vertical line through the pivot of the cover and the center of gravity is kept as close as possible to said line, thus making it easy to swing said cover to open or closed position. The downward movement of the cover-part may be limited by pins or stops 47 fixed to the cover-part and engaging the side edges of the body-part, and the upward movement of the cover-part may be limited by said stops engaging upwardly-extending portions 48 at the rear of the body-part. The cover-part terminates at the front some distance above the front wall 36 of the body-part, thus forming a slot through which various carriage-operating levers, such as the line-space lever 23, extend, to be operable from the outside of the casing. The slot may be closed by co-operating sound-deadening cushions 44 and 45 fixed to the cover-part and body-part, respectively, adjacent the edges of said slot.

When the cover-part moves to open position, its forward edge moves rearwardly and upwardly, and, especially where the cover-part has a large front-to-rear dimension, the forward edge would be raised to such height as to render it inconvenient for the operator to reach it when it is desired to lower the cover-part. The pivotal axis of the cover-part is therefore set some distance below the upper edge of the body-part, so that the forward

edge of the cover-part rises to a correspondingly lesser height, but sufficient to clear the machine and the work-sheets positioned therein. With this arrangement of parts, it is obvious that the rear edge 50 of the cover-part moves away from the upper rear edge 51 of the body-part when the cover-part is open. To prevent escape of sound at the meeting edges 50 and 51, when the cover-part is closed, the rear edge 50 overlaps the rear edge 51, and a sound-deadening cushion 52 may be interposed between the overlapping edges and fixed to one of said edges (here shown as edge 51). To prevent the leading edge of a work-sheet from catching on the upper rear edge 51 of the body-part as it is fed from the printing point over the platen and down behind the machine, the cover-part may be provided with a smooth overhanging portion 55 which overlies the upper rear edge of the body-part when the cover-part is in closed position.

By inspection of Figures 1 and 3, it will be seen that the body-part is provided with pockets 60, the sides of which are flush with the sides of the casing, and that the cover is pivoted on the headed screws or studs 49^a secured to the sides of said pockets. The floors of the pockets 60 may be formed by lateral extensions 61 at the rear of the base-plate 25.

To enable the hood to be placed over the machine, the various finger-pieces on the typewriter-carriage, including the line-space lever 23, may be detachably mounted on the carriage, as shown in my application, No. 466,820, filed May 4, 1921, (now Patent No. 1,519,645, dated December 16, 1924), said finger-pieces being secured to the carriage after the hood has been placed over the machine.

With this arrangement, it will be understood that both the machine and cabinet may readily be attached to a supporting base 65 which may form the drop leaf of a typewriter desk. For this purpose, there are provided two fastening devices 66, herein shown as screws passing upwardly through the drop leaf and through holes 67 in the base or floor 25 of the cabinet, said screws being threaded into lugs 68 of the typewriter frame 10.

Variations may be resorted to within the scope of the invention, and portions of the improvements may be used without others.

Having thus described my invention, I claim:

1. A sound-deadening assemblage for a typewriting machine having a frame and supporting feet therefor, said assemblage comprising a floor extending between the feet and the frame and to the sides and rear of the frame and having upstanding flanges at its side and rear edges, the feet extending below the floor, and a casing having overhanging carriage-accommodating

extensions and being settable down over the machine to rest on said floor in engagement with the sides of said flanges.

2. A sound-deadening assemblage for a typewriting machine having a frame and supporting feet therefor, said assemblage comprising a floor extending between the feet and the frame and to the sides and rear of the frame and having upstanding flanges at its side and rear edges, the feet extending below the floor, a casing having overhanging carriage-accommodating extensions and being settable down over the machine to rest on said floor in engagement with the sides of said flanges, and sprung-pressed latches on said casing for engaging the floor to secure the casing thereon.

3. A sound-deadening assemblage for a typewriting machine having a frame and supporting feet therefor, said assemblage comprising a floor extending between the feet and the frame and to the sides and rear of the frame and having upstanding flanges at its side and rear edges, the feet extending below the floor, and a casing having overhanging carriage-accommodating extensions and being settable down over the machine to rest on said floor in engagement with the sides of said flanges, the flanges being spaced from the edges of the floor sufficiently to permit the lower edge of the casing to rest on the floor outside of the flanges and be substantially flush with the edges of the floor.

35 4. A sound-deadening assemblage for a typewriting machine having a frame and supporting feet therefor, said assemblage comprising a floor extending between the feet and the frame and to the sides and rear of the frame and having upstanding flanges at its side and rear edges, the feet extending below the floor, a casing having overhanging carriage-accommodating extensions and being settable down over the machine to rest on said floor in engagement with the sides of said flanges, and means for removably securing said casing to said floor.

5. A sound-deadening assemblage for a typewriting machine having a carriage comprising a casing settable down over the machine and having overhanging extensions to accommodate the travel of the carriage, and a paper-accommodating pocket at the rear extending to the bottom of the casing and from end to end of the overhanging extensions, and a casing-supporting floor secured to the machine and provided with flanges for positioning said casing and forming the bottom of the pocket and also forming a closure for the bottom of the typewriting machine.

6. A sound-deadening assemblage for a typewriting machine having a frame with a forwardly-projecting keyboard extension,

feet secured to the bottom of the frame, and a carriage, said assemblage comprising a casing settable down over said machine and having a front wall with an opening to receive said keyboard extension, and a casing-supporting floor secured to the base by said feet and shaped to fit the bottom of said casing and having flanges adjacent its edges to extend upwardly inside of the lower edges of the casing to position the latter on the floor, a depressed portion between the feet to avoid interference with operating parts, and a flange at the forward edge of said depressed portion extending upwardly into said keyboard extension.

7. A sound-deadening casing for a typewriting machine, comprising a body-part, a cover, means for mounting said cover on said body-part, so as to move both the forward and rearward edges of the cover away from the body-part, a single tubular cushion to prevent the escape of sound between the cover and the body-part at the rear, and two tubular cushions to prevent the escape of sound at the front.

8. A cover for a sound-deadening casing for a typewriting machine, comprising side walls having downward extensions for pivotally supporting the cover, a rear wall having its lower edge considerably above the lower edges of the side walls and curved forwardly to avoid too great height for the cover, and a window extending forwardly and downwardly from the forward edge of said rear wall.

9. A sound-deadening casing for a typewriting machine, comprising a body-part settable down over the machine and having overhanging extensions to accommodate the carriage travel, a paper-receiving pocket at the rear extending downwardly from said extensions and from end to end thereof, and a rear wall extending substantially to the top of the machine, and a cover having a top extending from a line substantially at the top of the machine at its front, rearwardly at a small inclination above the horizontal, to a line slightly to the rear of the center of the machine, and then downwardly around the upper edge of the rear wall of the body-part adjacent its rear face, and side walls having downward extensions, so pivoted on the side walls of said pocket that the cover may be swung back of the body-part without causing any part of the cover to be raised substantially above the level of the highest part of the cover when in closed position.

10. A sound-deadening casing for a typewriting machine, comprising a body-part settable down over the machine and having a rear wall extending substantially to the top of the machine, and side walls having lateral extensions to accommodate the travel

- of the carriage, pockets extending downwardly from the lateral extensions and outwardly to the ends thereof, and upward projections extending to the top of the rear wall, and a cover having a top extending from a line substantially at the top of the machine at its front, rearwardly at a small inclination above the horizontal, to a line slightly to the rear of the center of the machine, and then downwardly around the upper edge of the rear wall of the body-part adjacent its rear face, side walls having downward extensions, so pivoted on the side walls of said pockets that the cover may be swung back of the body-part without causing any part of the cover to be raised substantially above the level of the highest part of the cover when in closed position, and pins extending inwardly from the side walls of the cover to engage the lateral extensions of the side walls to support the cover in closed position and to engage said upward projections to limit the rearward movement of the cover.
- 25 11. A sound-deadening casing for a type-writing machine, said casing comprising a body-part and a cover-part, said cover-part being pivoted to said body-part, the pivotal axis of said cover-part being positioned between the forward and rearward edges thereof, the rear edge of said cover-part moving away from the upper rear edge of said body-part when said cover-part is opened, the rear edge of said cover-part overlapping the upper rear edge of said body-part in the closed position of the cover-part to prevent the escape of sound between said parts.
- 40 12. A sound-deadening casing for a type-writing machine, said casing comprising a body-part and a cover-part, said cover-part being pivoted to said body-part, the pivotal axis of said cover-part being positioned between the forward and rearward edges thereof, the rear edge of said cover-part moving away from the upper rear edge of said body-part when said cover-part is opened, the rear edge of said cover-part overlapping the upper rear edge of said body-part in the closed position of the cover-part, and sound-deadening means interposed between said overlapping edges to prevent the escape of sound between said parts.
- 45 13. A sound-deadening casing for a type-writing machine, said casing comprising a body-part and a cover-part, said cover-part being pivoted to said body-part, the pivotal axis of said cover-part being positioned between the forward and rearward edges thereof, the rear edge of said cover-part moving away from the upper rear edge of said body-part when said cover-part is opened, the rear edge of said cover-part overlapping the upper rear edge of said body-part in the closed position of the cover-part to prevent the escape of sound between said parts, and means for preventing the catching of the ends of work-sheets on the upper rear edge of the body-part.
- 50 14. A sound-deadening casing for a type-writing machine, said casing comprising a body-part and a cover-part, said cover-part being pivoted to said body-part, the pivotal axis of said cover-part being positioned between the forward and rearward edges thereof, the rear edge of said cover-part moving away from the upper rear edge of said body-part when said cover-part is opened, the rear edge of said cover-part overlapping the upper rear edge of said body-part in the closed position of the cover-part to prevent the escape of sound between said parts, and means for preventing the catching of the ends of work-sheets on the upper rear edge of the body-part, said means comprising a portion fixed to the cover-part and overhanging the upper rear edge of the body-part in the closed position of the cover-part.
- 55 15. A sound-deadening casing for a type-writing machine, said casing comprising a body-part and a cover-part hinged to said body-part, said body-part having a rearward projection, and means carried by said cover-part and engaging said body-part to limit the downward movement of the cover-

body-part in the closed position of the cover-part, and a sound-deadening cushion fixed to one of said edges and compressed between said overlapping edges to prevent the escape of sound between said parts. 70

14. A sound-deadening casing for a type-writing machine, said casing comprising a body-part and a cover-part, said cover-part being pivoted to said body-part, the pivotal axis of said cover-part being positioned between the forward and rearward edges thereof, the rear edge of said cover-part moving away from the upper rear edge of said body-part when said cover-part is opened, the rear edge of said cover-part overlapping the upper rear edge of said body-part in the closed position of the cover-part, and a sound-deadening cushion fixed to the upper rear edge of said body-part and compressed by the overlapping edge of said cover-part to prevent the escape of sound between said parts. 80

15. A sound-deadening casing for a type-writing machine, said casing comprising a body-part and a cover-part, said cover-part being pivoted to said body-part, the pivotal axis of said cover-part being positioned between the forward and rearward edges thereof, the rear edge of said cover-part moving away from the upper rear edge of said body-part when said cover-part is opened, the rear edge of said cover-part overlapping the upper rear edge of said body-part in the closed position of the cover-part to prevent the escape of sound between said parts, and means for preventing the catching of the ends of work-sheets on the upper rear edge of the body-part. 90

16. A sound-deadening casing for a type-writing machine, said casing comprising a body-part and a cover-part, said cover-part being pivoted to said body-part, the pivotal axis of said cover-part being positioned between the forward and rearward edges thereof, the rear edge of said cover-part moving away from the upper rear edge of said body-part when said cover-part is opened, the rear edge of said cover-part overlapping the upper rear edge of said body-part in the closed position of the cover-part to prevent the escape of sound between said parts, and means for preventing the catching of the ends of work-sheets on the upper rear edge of the body-part, said means comprising a portion fixed to the cover-part and overhanging the upper rear edge of the body-part in the closed position of the cover-part. 100

17. A sound-deadening casing for a type-writing machine, said casing comprising a body-part and a cover-part hinged to said body-part, said body-part having a rearward projection, and means carried by said cover-part and engaging said body-part to limit the downward movement of the cover- 110

part, said means engaging the rearward projection of the body-part when the cover-part is opened to limit the upward movement of the cover-part.

5 18. The combination of a typewriting machine, a drop leaf of a desk to support said machine, a sound-deadening casing for said machine, comprising a floor secured to said machine and having holes therein, and screws passing through said drop leaf through the holes in the floor of said casing and threaded into the frame of said machine to hold said machine and casing on said drop leaf.

15 19. The combination of a typewriting machine having a main frame, supporting feet secured to the main frame, a sound-deadening casing for said machine, said casing comprising a hood to fit over the machine and a floor introduced between the bottom of the

20

frame and the feet of the machine, a supporting base to be engaged by said feet, devices to hold said machine on said base, and devices to hold said hood on its floor.

25 20. The combination of a typewriting machine having a main frame, supporting feet on said main frame, a sound-deadening casing for said machine, said casing comprising a hood to fit over the machine and a floor introduced between the bottom of the frame and the feet of the machine, said floor having holes therein, a supporting base, forming the drop leaf of a desk, to be engaged by said feet, screws passing through the drop leaf and through the holes in said floor and threaded into said frame to hold said machine on said drop leaf, and releasable latches to hold the hood on its floor.
